SPARK-PLUG.

1,316,904.

Specification of Letters Patent. Patented Sept. 23, 1919.

Application filed October 21, 1918. Serial No. 259,113.

To all whom it may concern:

Be it known that I, JAMES A. LAING, a citizen of the United States, residing at Spokane, in the county of Spokane and State 5 of Washington, have invented certain new and useful Improvements in Spark-Plugs, of which the following is a specification.

The present invention relates to an improved spark plug which is designed especially for overcoming existing difficulties and objectionable features in spark plugs for internal combustion engines. The primary object of the invention is to improve the clamping features of the plug for the wire 15 terminals, so that these terminals may be maintained free from foreign matter that would render the contact defective, and thus avoid poor circuit making with its consequent troubles.

20 The invention consists in certain novel combinations and arrangements of parts involving the use of a metal cup or cap on one of the clamping nuts for the terminal wires, and in the means for attaching said cup to 25 the clamping nut, as will be hereinafter pointed out in the specification and claims.

In the accompanying drawings one complete example and a slight modification thereof is illustrated, showing the physical 30 embodiment of the invention constructed and arranged according to the best mode so far devised for the practical application of the principles of the invention.

Figure 1 is a view, showing the end of a 35 spark plug of usual type with the clamping nut and terminal cup or cap therein, embodying the present invention.

Fig. 2 is a similar view showing a clamp nut of somewhat different shape.

40 Fig. 3 is an enlarged view showing the clamp nut and the terminal cap attached thereto and illustrated in section.

The invention is applicable for use in connection with practically all standard forms 45 of spark plugs which usually include the porcelain, insulating post 1, the metal cap 2 thereon and the conductor stem 3 with its threaded end for the wire terminal clamping nut 4. Preferably the clamping nut is 50 of the butterfly type having the wings 5, 5,

so that the nut may be turned on the threaded stem, without recourse to tools, which often cause breakage of the porcelain post.

At the base of the nut, which is preferably cylindrical, is provided a brass cup 6, also 55 cylindrical in shape and provided with the annular flange 7 to fit around the end of the nut, there being an opening 8 in the center of the cup for the conductor stem. The cup is formed with an annular rib 9, which is of 60 V-shape in cross section thus providing it with a tapered interior which is adapted to embrace and fit over the loop formed in the terminal wire when said loop is placed over or hooked around the stem 3. After the 65 terminal is placed about the stem, the nut is turned "home" and the tapered cup, as it is turned in close contact with the loop, forces the loop up against the bottom 8' of the cup to make the proper contact. The 70 friction between the wire loop and the interior of the cup insures a clean surface of these parts, and of course the clean surface insures a good terminal contact for the wires. The terminal loop is clamped between 75 the cup 6 and the cap 2, on the end of the porcelain post, and thus a positive contact and connection are provided for the terminal wires.

To retain the cup 6 on the end of the 80 clamp nut, a series of grooves 10 are provided in the exterior surface of the nut, which grooves are of bayonet formation, and adapted to receive the boss or bosses 11, projecting from the interior surface of the wall 85 or flange 7. These bosses are stamped or struck up from the metal of the flange and fit neatly in the grooves so that they may move in the grooves when the nut is turned, toward either end of the groove, but will 90 retain the cup on the end of the nut. The cup may readily be attached or detached through the instrumentality of the boss-and-groove construction, when required.

Claims:

1. The combination in a spark plug with the clamp nut thereon, of a metallic cup having interiorly projecting bosses and grooves for said bosses in the exterior surface of the nut whereby the cup is retained on the nut, 100

and said cup having a portion thereon to frictionally engage the wire terminal for the electrical connection to the plug.

2. The combination in a spark plug with 5 the clamp nut thereon, of a metallic cup having interiorly projecting bosses and grooves in the exterior face of the nut for

said bosses to retain the cup on the nut, a projecting rib on the cup of circular formation and V-shape in cross section and adapted to clamp the wire terminal on said cap, as described.

In testimony whereof I affix my signature.

JAMES A. LAING.
